CHARLES G. BROSTROM, OF LYNN, AND ANDREW R. RIDDERSTROM, OF NAHANT, MASSACHUSETTS, ASSIGNEES TO BEACON FOLDING MACHINE COMPANY, OF LYNN, MASSACHUSETTS, A CORPORATION OF MASSACHUSETTS.

FOLDING MACHINE.

Original application filed May 12, 1917, Serial No. 168,165. Divided and this application filed February 11, 1924. Serial No. 692,103.

To all whom it may concern:

Be it known that we, CHARLES G. BROSTROM and ANDREW R. RIDDERSTROM, citizens of the United States, and residents, respectively, of Lynn and Nahant, in the county of Essex and Commonwealth of Massachusetts, have invented a new and useful Improvement in Folding Machines, of which the following is a specification.

10 The present invention relates to machines for folding flexible material. The present application is a division of a copending application, Serial No. 168,165, filed May 12, 1917.

15 The present invention is hereinafter described, and is illustrated in the accompanying drawings, in connection with a machine for folding or turning over the margins or edges of boot and shoe uppers, such as 20 vamps, tips and the like. The invention is not, however, restricted to machines of this character, but has also other and more general fields of usefulness. Machines for folding binding strips around the edges of shoe 25 uppers to which they are sewed, machines for turning the channel flaps of channeled shoe soles, and other machines for folding flexible material are all included within the present invention. In order to avoid 30 cunlocution of language, all such machines will hereinafter be included in the specification and, more particularly, in the claims, under the generic term, "folding machine;" and it will be understood that the term 35 "margin" or the term "edge" will be employed herein to denote not only the border portions of a shoe upper, but also a marginal binding strip, the channel flap of a channeled sole, and other such parts that 40 are intended to be folded in the defined "folding machine."

According to present-day practice in shoe manufacture, after the margin of a boot or shoe upper has been cemented, the upper is 45 introduced into the machine, in which it is advanced, step by step, past a knife and a folder or plow, to a fold presser, or hammer. The knife is controlled to snip the margin, when desired, the plow acts to initiate the 50 fold, and the fold thus initiated is pressed down by the fold presser, being held in pressed condition by the cement.

A very important object of the present in-

vention is to improve upon present-day methods and machines, to the end that a 55 better and a better-controlled initial fold or turn may be produced.

In present-day, commercial folding machines the feed mechanisms of which comprise vibratory feed points and feed blocks, 60 the feed elements are operated by spring-controlled cams. Owing to inherent time lags, the feed elements can not respond readily enough to the action of the operating instrumentalities, and so can not be employed in high-speed machines. A feature of the 65 present invention, accordingly, contemplates a positive connection between the feed elements and their operating instrumentalities, thus eliminating the above-referred-to time 70 lags.

If the stock is advanced by relatively short feed strokes, sharp curves will be folded more readily. The comparative slowness of 75 operation resulting from the use of short feed strokes may be compensated for by operating the machine at higher speed. In fact, if the speed of operation is high enough, the folding operation as a whole may be increased to a value above that commonly prevailing. Curved portions of the work, 80 however, should be advanced less rapidly than straight portions, so that a small portion only of the margin may be folded at any one time, and a better approximation thereby 85 attained to a smooth, curved fold. A further object of the invention, therefore, is to provide improved means controlled manually, preferably by a progressively movable treadle, for gradually moving the feed elements 90 relatively towards and from each other, to increase and decrease gradually the length of the feed strokes. To the attainment of 95 this end, a feature of the invention resides in swinging one of the feed members, as the upper feed point, from its operating point as a fulcrum, so as to render it effective to a varying extent during different feed strokes. According to the specific embodiment of the invention that is herein illustrated and described, the feed point is carried by a leaf spring that is secured to its 100 operating device at a point relatively remote from the feed point.

A still further object is to provide an improved, manually controlled construction,

comprising a single treadle, for controlling the power clutch and also for elevating and depressing the upper feed point, to render the same varyingly effective or ineffective, at will. By actuating the treadle, therefore: first, the clutch may be thrown in, to start the machine; and then, by a further movement of the treadle, the feed point may be depressed and the effective feed movement started.

A further object is to provide for swinging the work table back over the frame and the operating mechanism of the machine. In the illustrated embodiment of the invention, the table is pivoted to the frame at a point relatively remote and far back from the working point of the horn; this permitting the table to be moved out of the way, as required for handling cylindrical vamps, without taking the table off the machine.

One important object of the present invention has to do with improved means for performing the snipping operation in a manner so that the depth of the cuts may be gradually varied as the folding progresses, making it possible to start with a very small or shallow snip or cut at the beginning of a concave edge portion, and thence gradually increase the depth of the snips to the required maximum depth. In this way it is insured that the fold will be smooth and even, without a break or hump in the stock that is apt to occur at the point where the snipping begins when the snipping is started at maximum depth according to present usual practice.

The foregoing and other objects and advantages of the invention will more fully appear from the following detailed description, and the distinctive features of novelty will be pointed out in the appended claims.

Referring to the drawings, Fig. 1 is a central, longitudinal, vertical section of a machine constructed in accordance with the present invention; Fig. 2 is a fragmentary detail, illustrating the immediate working parts in side elevation; Fig. 3 is a detail front view of the machine; Fig. 4 is a partial view of the front of the machine, with certain parts removed, and others in section upon the line 4—4 of Fig. 1, looking in the direction of the arrows, to illustrate the immediate working elements; Fig. 5 is a sectional detail on line 5—5 of Fig. 1, looking in the direction of the arrows; Fig. 6 is a fragmentary perspective, showing a vamp and the immediate working parts in operative relation thereto; Fig. 7 is a fragmentary detail, in section upon the line 7—7 of Fig. 2, looking in the direction of the arrows, also showing the immediate working parts in operative relation to a vamp; Fig. 8 is a vertical section taken upon the line 8—8 of Fig. 1, looking in the direction of the arrows, showing the working parts in detail,

acting on a vamp; and Fig. 9 is a detail similar to Fig. 8, showing the operative parts occupying another position.

The frame or housing of the machine comprises a body portion 10, extending up into a curved overhanging portion 11, with a forwardly extending nose 12. The nose 12 is spaced from the body of the frame above an extension 13, the extension 13 constituting what is known as the "horn" of the machine. The frame is equipped with a bearing 14 to receive the rear portion of a drive shaft 15, in substantially the plane of the feed elements, referred to below. The forward end of this shaft is journaled in a separate bearing bracket or sleeve 16, which may be rigidly secured to the frame by a cross pin or rod 17. For adjustably centering the bearing sleeve 16, transverse screws 115 are fitted from opposite sides, through web portions of the machine housing, to engage the sleeve at opposite points.

A hand-and-balance wheel 18 is keyed or otherwise suitably secured upon the outer end of the shaft 15, and is provided with a clutch face 19. The clutch face 19 is adapted to be frictionally engaged by a co-operative clutch face on the inner side of a driving pulley 20 that is fitted on a sleeve 21. The clutch face of the pulley 20 is normally held away from the clutch face 19 by a coil spring 22 that is housed in a recess between the wheel 18 and the pulley 20. The sleeve 21, which is slidably fitted loosely on the shaft 15, has a head 9. The pulley 20 is maintained in engagement with the head 9 by the spring 22. A head 23 is fitted in the outer end of the sleeve 21 and is engageable by a wear button 24, that is constituted of fibre or the like, and that is carried at the upper, outer end of a lever arm 25. The lever arm 25 is pivoted to the frame at 26 and is rigidly provided with a long, horizontally extending arm 27. The arm 27 reaches most of the way toward the front of the housing, where its extremity is slotted to receive therein, with a capability of endwise sliding, a pivot block 28. The pivot block 28 is carried at one end of a short, lever, link bar 29, the other end of which is pivoted at 30 to the end of one arm 31 of a bell-crank lever. The bell-crank lever is fulcrumed at 45 and its other arm 32 has an adjustable stop pin 33 fitted in its extremity adapted to engage the frame as an abutment to limit the swinging movement of the said lever in one direction. The swinging of the said lever in the other direction is yieldingly limited by an adjustable headed bolt 34 threaded into the frame and having a coil spring 35 interposed between its head and a seat in the lever arm 32. The lever bar 29 is pivotally connected at an intermediate point 36 to a depending bracket 37, the pivot connection 36 being, as shown, nearer to the pivot block 130

28 than to the pivot 30, for a reason that will later appear. The bracket 36 has a shoulder 38 formed thereon underneath the pivot 36 and is equipped with a depending pin 39 5 slidably fitted through a bearing strut 40 of the frame. A compression coil spring 41 is interposed between this strut and the shoulder 38. Upon release of the treadle, the coil spring 41 will return the lever arms 27 and 10 31 to their illustrated, ineffective positions, permitting the spring 22 to disconnect the clutch faces and also elevating the feed point, as will later appear. The bracket 37 is provided with an offset portion having a 15 pivot connection 42 to a depending rod 43. The rod 43 is adapted to be connected to a treadle (not shown), and typifies any suitable control, preferably manual, for the power clutch and also for the upper feed 20 point.

For applying a brake to the machine by the same operating device that controls the power clutch, a short, brake lever arm 104 is mounted on the pivot 26. The arm 104 is 25 provided with a brake shoe 105 that is adapted to engage the periphery of the wheel 18. The arm 104 has a downward extension 106 below its pivot 26, where it is engaged by a screw 107 that is adjustably carried in a lug 108, rigid with and depending from the arm 25. Thus, upon an upward movement of the arm 27, to disengage the driving-clutch elements, the pin 107, by engaging the extension 106, applies the brake at a time predetermined by the adjustment of the screw 107.

The lower end of a vertically disposed link bar 46 is pivoted to the lever arm 31 at 44, relatively close to the fulcrum 45. The upper end of the link bar 46 is pivoted at 47 40 to the inner end of a frame plate 48. The frame plate 48 is pivoted to swing in a vertical plane about a pivot pin 49 that is transversely fixed in the frame of the machine, and is provided with a vertically disposed 45 pivot post 50. The base of a bracket mounting 51 is pivoted to swing or rock horizontally about the post 50 as an axis, on a bearing surface provided at the top of the plate 48. A lower feed block 53 is clamped, as 50 shown at 52, to the forward end of the bracket mounting 51, and is provided with a plow 116 for turning up the margin of the stock, as will be more fully explained later. The bracket mounting 51 has spaced-apart, 55 rearward, wing extensions or ears 54, bearing a transverse pivot pin 55 that constitutes a pivot or axis for a lever arm 56. The lever arm 56 is thus adapted to swing vertically on an intermediately disposed pivot pin 55 60 that is transversely secured between the extensions or ears 54, and also, with the mounting 51, to swing or rock horizontally about the vertical pivot pin 50. A leaf spring, in the form of a resilient plate 58, is clamped 65 to the lever arm 56, at its inner end, and rel-

atively remote from the pivot 55, as seen at 57. The leaf spring 58 extends forward well beyond the pivot 55, to constitute a resilient yielding mounting for the upper feed member 59 which, as shown, is integral with the said spring plate. This upper feed member comprises a downwardly and inwardly turned extremity, terminating in a downwardly projecting feed point 60, opposite the lower feed block 53. By means of 70 this construction, the use of separate, spring-controlled cams is rendered unnecessary, so that the feed elements may be positively connected to their operating instrumentalities. The inner end of the lever arm 56 is 75 formed with a socket 61, in which is fitted a ball head, mounted on a crank pin 62, which is carried at the end of the drive shaft 15.

As the shaft 15 is rotated, the lower feed block 53 is oscillated by the crank pin 62 in 80 a horizontal plane about the axis 50. The upper feed member 59 also partakes of this horizontal oscillation and is at the same time endowed with a vertical oscillation about the horizontal axis 55. It is in consequence of 85 the horizontal oscillations that the feed members are caused to produce the feed movement, and the vertical oscillation causes the feed point to grip and release the work alternately. The path that the feed point 60 follows is curved, generally oval, in nature. The feed point presses the material against the lower block 53 whenever the treadle rod 43 is depressed. Depression of the treadle 90 rod effects a downward movement of the link bar 46 and a corresponding swinging movement of the plate 48 about the pivot pin 49. This movement of the plate 48 results in a relative movement towards each 95 other of the feed block and the feed point, both of which it supports. The more that the treadle rod is depressed, the closer will the feed point and the feed block be caused to approach each other; with the result, as 100 the feed point is carried by the spring plate 105 58, and yields upward by spring action, that the oval path of the feed point will become 110 more and more flattened. The flatter the oval path of the feed point, the sooner will 115 the material be engaged between the feed point and the feed block on each feeding movement, and the longer will each such engagement take place. The arm 56, carrying 120 the feed point, of course, moves through the same range, with the feed block, during every intermittent feed movement; but the feed point is caused to engage the material earlier and earlier, before the completion 125 of its downward movement, the farther and farther that the treadle rod is depressed. According to the degree of depression of the treadle, therefore, the feed point may be caused to engage the material to feed it through longer or shorter feed strokes, as 130 desired.

The mounting 51 is equipped with an adjustable stop screw 63, adapted to determine the final limit of downward movement of the feed point 60, and the frame is equipped 5 with spaced stops 64, 65 for co-operation with the bell-crank lever arms 31 and 32. The stops 64 and 65 limit the described operative movement of the treadle in opposite directions, thereby determining the final 10 limits of feeding movement of the upper and lower feeding elements.

For performing the snipping operation in concave margins of the stock, a movable knife 66 is provided for co-operation with 15 a fixed knife block 67 mounted on the horn portion of the frame. The knives are held against movement in the line of feed. The knife 66 is clamped for limited vertical adjustment by means of an elongated slot and 20 clamp screw, as indicated at 68, at the end of the outer arm of a lever 69. The lever 69 is pivoted at 70 and is provided with an inwardly extending, bent arm the extremity of which is pivotally connected at 71 to 25 one end of a pitman rod 72. The other end of the pitman rod 72 is connected to a crank pin 73 that is carried by a spiral gear 74 journaled on a pivot 75 carried by the frame. The spiral gear 74 is in driven engagement 30 with a co-operative spiral gear 76 that is fixed on the drive shaft 15. It will be noted that the spiral gear 76 is only one-half the diameter of the spiral 74, the purpose of this being to obtain a reduction in the driven 35 ratio from the shaft 15 to the snipping knife, since, on account of the relatively short feed strokes of the present machine, as described, it is not necessary that a snipping cut be made at every feed stroke but, 40 in practice, it is found that such a snip cut at every other feed stroke is amply sufficient. The pivotal point 70 is adjustable, to vary the depth of the snip cuts produced by the knife. For this purpose, the pivot pin is 45 carried at the end of a swinging arm 77 fulcrumed to a pivot pin of the frame at 78. Also engaged with the pivot pin 70 is a link bar 79, the other end of which is pivoted at 80 to the short arm of a bell crank lever 81 50 which is pivoted to the frame at 82 and has its longer horizontally extending arm pivotally connected at 83 to a downwardly extending treadle rod 84 which may have associated therewith a suitable treadle, or like 55 manual operating device (not shown). It will be noted that the mounting arm 77 extends from its pivot generally transverse of the direction of the knife-carrying lever 69 and thus a swinging adjustment of said arm, 60 as effected by the treadle of the rod 84, will shift the knife 66 transversely with reference to the line of feed of the stock as produced by the feed point 60 and feed block 53, thus causing the knife 66 to snip in to 65 a greater or less depth according to the

swinging adjustment of said arm mountings 77. The arm 77 has formed therewith opposite transversely extending lugs 85, 86, the former engageable by an adjustable set screw 87 fitted into the frame housing and 70 the latter engageable with a stop screw 88 adapted to be set in fixed adjustment. The adjustable stop screw 87 is at the forward side of the arm 77 and thus its adjustment will determine the extent to which the knife 75 66 may be set outward, i. e., to determine the maximum depth of the snip cut, while the setting of the stop 88 will determine the possible inward movement of the knife upon retraction thereof. For normally holding 80 the knife 66 at its outer limit of movement a suitable coil spring is provided to react against a lug of the frame housing, and press upward against a collar adjustably fixed on the treadle rod 84, as is illustrated in the 85 drawings of the aforesaid application Serial No. 168,161.

For completing the folding over of the margin of the vamp, after it is turned up by the plow on the lower feed block, as more 90 fully explained later, and for hammering or pressing down the same, a hammer 92 is provided which, as shown more particularly in Fig 3, is pivoted to the same pivot pin 49 that serves as a pivot for the mounting 48. 95 The hammer 92 is held from movement in the line of feed and is normally inclined, extending obliquely upward and outward. Its lower end is pivotally connected to a collar 93 that is slidably carried on an operating rod 94. The collar 93 is held for limited movement between a stop collar 95 on the rod 94 and a stop head 96 carried at the end of the said rod, and is normally held yieldingly against the collar 95 by a coil 100 spring 97 that is interposed between the collar 93 and the head 96. The inner end of the rod 94 is pivotally connected at 105 98 to the lower end of a short lever 99. The lever 99 is fulcrumed to the frame at 110 100 and its upper end is provided with a contact piece 101 that is engageable with a cam face 102 fixed on the shaft 15. A coil spring 103 is anchored to the pivot 100 and engages the upper portion of the lever 99, 115 thus pressing the said upper end of the said lever constantly against the cam 102. The hammer 92 is therefore oscillated in timed relation to the feed movements. The hammer blows are rendered yielding or resilient 120 to the required extent by reason of the interposed spring 97, while the upward movement of the hammer is rendered positive by engagement of the fixed collar 95 with the slide collar 93.

In machines of this kind, it is desirable to be able to move the table out of the way when operating upon certain kinds of work, such as so-called "cylindrical" vamps. Heretofore, it has been customary to remove 130

the table altogether. But to dismount the table from the machine requires some little time and involves liability of losing the securing parts during assembling and disassembling. According to the present invention, the table is pivoted to the machine frame or housing at a point relatively far back, and remote from the horn, so that it may be swung up and backward over the horn and housing, and out of the way of the operator, without taking the same off from the machine. The table is indicated at 109, and is shown fitted around the platform 110 at the front of the horn, this platform being a relatively small plate block adjustably clamped to the top of the horn, and the table 109 being recessed, as seen at 111, to fit down over the same. The table has projections 112 at each side of the machine housing, extending to a point well rearward thereof, where their extremities are fulcrumed, as seen at 113, to transverse pivots carried by the housing. The forward portion of the table is adjustably supported by prop posts 114 that are vertically threaded into the frame housing at each side thereof, the adjustment of these prop posts permitting the table to be adjustably set so that its top surface will be approximately flush with the surface of the platform 110.

Referring now more particularly to the immediate working parts, as hitherto explained, the stock is gripped for feeding between the lower feed block 53 and the upper feed point 60. On the lower feed block 53 is carried the "plow" or folder 116, presenting a curving face of changing outline, as shown more particularly in Fig. 6, adapted to catch the horizontally extending edge of the vamp V and turn the same up to an approximately vertical position. The feed point and the feed block 53 are adapted to engage the material at a point such that the line joining this point to the plow 116 is substantially at right angles to the line of feed. The plow and the feed elements are therefore as effective, both to fold and to feed, at sharply curved portions of the margin, as at straight portions. If the plow were at a substantial distance forward of the feed elements, for example, a sharply convex portion of the stock would be moved by the feed elements out of range of the plow, so as not to be folded at all thereby, and a sharply concave portion would be folded too far over by the plow. The hammer 92 is formed with a horizontal extremity for engaging that portion of the work that is located just beyond the feed members, along the line of feed. The operating mechanism is timed so that the hammer shall move down to grip the turned-over margin of the stock, as seen in Fig. 9, during the time that the feed members are moving backward, preliminary to getting a new grip

on the stock. In the said Fig. 9, the feed members are illustrated in the positions that they occupy just prior to their return movement. During this return movement, the plow 116, which moves with the feed block 53, performs the described operation of turning up the margin of the vamp. The upper feed point 60 is, as shown, provided with a forwardly projecting finger 117 that is adapted to extend over and engage and guide the margin of the stock, just in advance of the plow, so as to hold it against the plow and keep it from buckling up prematurely, prior to the action thereon of the plow. The snipping knife 66 is arranged just in advance of the plow 116, along the line of feed, as shown in Figs. 6, 7 and 8 and, as before explained, the operating device of this knife is preferably timed to cause it to operate once at every other feed movement; though it will be understood that this is merely illustrative, and that any desired ratio between the feed movements and the snipping operations may be obtained by selective changes in the spiral-gear drive for the snipping knife. Since the hammer 92 is mounted to extend obliquely upward and forward, its action on the edge of the stock will be in the same oblique direction, thus insuring the proper turning down of the margin of the vamp that has already been turned upward by the plow 116.

In use, the operator, introducing the vamp V into the machine, places the margin thereof on the lower feed block 53. At this time, when the machine is idle, the feed block is relatively depressed under the action of the spring 41, and the upper feed point 60 is correspondingly lifted, so that ample room is afforded for inserting the work. Upon depression of the treadle rod 43, the lever link 29, first swinging on the point 30 as a fulcrum, since the pivot 36 is nearer to the point 28, operates the lever 25, to throw in the clutch elements 19, 20, starting the machine. The feed members thereupon begin their cycle of movements, but still separated and ineffective. When the operator wishes to begin work, he now further depresses the treadle rod 43. This causes the link 29 to swing on the point 28 as a fulcrum, since this point can move no further, and the link 29 swings downward the lever 31, thus effecting a turning movement of the mounting 48 about the pivot 49 to elevate the feed block 53 into its effective plane. At the same time, the pivot 55 of the arm 56 is moved downward, causing this arm to swing downward about the bearing 61 as a fulcrum. The feed member 59 is thus actuated, with a multiplied movement into effective position. If the operator desires a relatively slow feed, he depresses the treadle rod 43 to a relatively lesser extent, which causes the feed point 60 of the

feed member 59 to engage the material through a small portion only of its lower range of movement. The feed point is in this manner caused to describe a relatively wide or broad oval path, so that the material is only moved forward a little at each step. If, however, a more rapid feed is desired, the treadle rod is depressed further, causing the arm 56 to become tilted further, and this will result in the spring-plate mounting 58 of the upper feed point becoming placed under spring tension. The feed point 60 will therefore engage the material sooner, and remain in engagement with it longer to effect a longer range of feed. At this time, the spring plate 58 yields resiliently to permit the arm 56 to continue operating in an oval path, though the feed point 60 is constrained to move, during this feed movement, in a straight path,—with the result that the feed point describes approximately a more or less flattened oval. The feed may thus be varied, at will, by depressing the treadle rod 43 to a greater or less extent, as desired by the operator. When it is desired to move the table 109 out of the way, it has only to be swung on the pivots 113 over past the vertical plane of its pivot point, as indicated in dotted lines at 109^a, in which position it may be left, out of the way of the operator, until such time as it is desired to use the table again.

The invention may be embodied in other specific forms as to its various details, and certain of the features of novelty described may be advantageously used apart from others of the present combination, and it is therefore desired that the present embodiment be considered in all respects as illustrative, and not restrictive, reference being had to the appended claims, rather than to the foregoing description, to indicate the scope of the invention.

What is claimed is:

1. A folding machine having, in combination, means for pressing a fold in a sheet of material, and means for feeding the material to the fold-pressing means comprising a movable support, two feed elements supported by the support, and means whereby movement of the support simultaneously effects movement of each feed element towards the other feed element.

2. A folding machine having, in combination, means for pressing a fold in a sheet of material, means for feeding the material to the fold-pressing means comprising two feed elements, and means for simultaneously moving each element towards and from the other element to render the feeding means variably effective.

3. A folding machine having, in combination, means for pressing a fold in a sheet of material, a movable base, a feed point and a feed block carried by the base for

feeding the material to the fold-pressing means, and manually controlled means for controlling the movable base.

4. A folding machine having, in combination, means for pressing a fold in a sheet of material, a movable rocking base, a feed point and a feed block carried by the base for intermittently feeding the material to the fold-pressing means, means for rocking the base to render the feeding means intermittently effective, and manually controlled means for controlling the position of the movable base.

5. A folding machine having, in combination, means for pressing a fold in a sheet of material, a feed point and a feed block for advancing the material to the fold-pressing means mounted and connected for relative yielding movement with respect to each other, whereby the feed point describes an orbital movement with respect to the feed block, and means for moving the feed block towards the feed point to shift the range of such orbital movement, whereby the feed point is caused to engage the material for a variable interval on each feed stroke.

6. A folding machine having, in combination, means for pressing a fold in a sheet of material, a rocking base, means for feeding the material to the fold-pressing means comprising a feed block carried by the base and a feed point pivoted to the base, the fold-pressing means being held from movement in the line of feed, and a driving shaft having a crank pin for rocking the base and relatively moving the feed block and the feed point.

7. A folding machine having, in combination, means for pressing a fold in a sheet of material, a movable support, two feed elements supported by the support for feeding the material to the fold-pressing means, movement of the support being adapted to effect a relative movement of the feed elements, a horizontally disposed shaft having a crank pin for effecting the movement of the support, and means for rotating the shaft.

8. A folding machine having, in combination, means for pressing a fold in a sheet of material, and means for feeding the material to the fold-pressing means comprising a substantially horizontally rocking support, a feed block secured to the support, a feed point pivoted to the support, and a driving shaft substantially in the plane of feeding movement having a crank pin for rocking the support and actuating the feed point relatively to the feed block.

9. A folding machine having, in combination, means for pressing a fold in a sheet of material, and means for feeding the material to the fold-pressing means comprising a substantially horizontally disposed feed member, a resiliently operable feed

point carried by the feed member, and a substantially horizontally disposed arm connected for vibration to which the feed member is secured at a point relatively remote horizontally from the feed point.

10. A folding machine having, in combination, means for pressing a fold in a sheet of material, means for intermittently feeding the material to the fold-pressing means comprising a vibratory feed block and a co-operating vibratory feed point pivoted to the feed block, and a driving shaft having an eccentric positively connected to one of the feed elements, whereby the feeding means is adapted to be vibrated at relatively high speed.

11. A folding machine having, in combination, a hammer, and means for feeding material to the hammer comprising a leaf spring disposed substantially in the plane of feed and a feed point carried by the leaf spring.

12. A folding machine having, in combination, means for pressing a fold in a sheet of material, means for feeding the material to the fold-pressing means comprising two feed elements that are both spring-pressed towards each other, and means for varying the spring pressure during the operation of the machine.

13. A folding machine having, in combination, means for pressing a fold in a sheet of material, and means for feeding the material to the fold-pressing means comprising a substantially horizontally disposed feed member, a resiliently operable feed point carried at the forward end of the feed member, a substantially horizontally disposed arm connected for vibration to which the feed member is secured at a point relatively remote from the feed point, and a horizontally disposed driving shaft having a crank pin positioned near the rear end of the feed member for actuating the same.

14. A folding machine having, in combination, means for pressing a fold in a sheet of material, and means for feeding the material to the fold-pressing means mounted and connected for vibration and comprising a lower feed block and an upper feed point, both pivoted to swing horizontally, and the upper feed point also pivoted to swing vertically about a pivot fixed with respect to the feed block, and means for shifting the pivot to cause the feed point to swing from its operating point as a fulcrum for moving the feed point into and out of operative position.

15. A folding machine having, in combination, means for pressing a fold in a sheet of material, and means for feeding the material to the fold-pressing means comprising a feed point mounted to swing about an axis in one plane for feed movement, and about an axis in a plane transverse thereof

for movement into and out of engagement with the material, means for operating the feed point by engagement with one extremity of the mounting thereof to vibrate the same on an intermediate pivot, and means for manually raising and lowering the pivot to swing the feed point into and out of operative position from its operating point as a fulcrum.

16. A folding machine having, in combination, means for pressing a fold in a sheet of material, and means for feeding the material to the fold-pressing means comprising a leaf spring disposed substantially in the plane of feed, an upper feed point carried by the leaf spring, and an arm also disposed substantially in the plane of feed connected for vibration to which the spring is fixed at a point relatively remote from the feed point.

17. A folding machine having, in combination, means for pressing a fold in a sheet of material, and means for feeding the material to the fold-pressing means comprising a leaf spring, an upper feed point carried by the leaf spring, and an arm mounted and connected for vibration about axes in two planes at an angle to each other, the spring being fixed to the arm at a point relatively remote from the feed point, whereby the feed point receives a yielding orbital movement therefrom.

18. A folding machine having, in combination, means for pressing a fold in a sheet of material, and means for feeding the material to the fold-pressing means comprising a lower feed block and an upper feed point mounted and connected for swinging vibration, the feed point being separately mounted for yielding swinging vibration and adjustment toward and from the feed block, and means for adjusting the feed point toward and from the feed block with the machine in operation.

19. A folding machine having, in combination, means for pressing a fold in a sheet of material, and means for feeding the material to the fold-pressing means comprising a lower feed block and an upper feed point both mounted for horizontal vibrating movement, the upper feed point being mounted also for yielding vertical swinging vibrations, means for imparting the said movements to the said feeding means, and means for moving the upper feed point toward and from the lower feed block during the operation of the machine, whereby the extent of the operative feed strokes may be varied.

20. A folding machine having, in combination, means for pressing a fold in a sheet of material, means for feeding the material to the fold-pressing means comprising a feed point that is normally ineffective when the machine is in operation, driving

means for the fold-pressing and the feeding means, and treadle-controlled means for first rendering the driving means effective and then rendering the feed point variably effective.

21. A folding machine having, in combination, means for pressing a fold in a sheet of material, and means for feeding the material to the fold-pressing means connected for vibration and comprising a feed point movable into and out of effective position without disturbing its operative movements, driving means for the feeding means comprising a disconnecting clutch, and connections for controlling the clutch and also for controlling the position of the feed point having a single manual operating device.

22. A folding machine having, in combination, means for pressing a fold in a sheet of material, and means for feeding the material to the fold-pressing means connected for vibration and comprising a feed point movable into and out of effective position without disturbing its operative movements, driving means for the feeding means comprising a disconnecting clutch, and connections for controlling the clutch and also for shifting the feed point into and out of effective position, the said connections extending to a single operating device with an interposed pivotal linkage, whereby the manual operating device first actuates the clutch and by a further movement brings the feed point into effective position.

23. A folding machine comprising feeding mechanism mounted and connected for vibration to feed sheet material intermittently forward by gripping its margin, folding means associated therewith, and a snipping device associated with said feeding mechanism and having operative connections for vibrating it in timed relation to the vibration of said feeding mechanism and in a definitely reduced ratio with respect thereto.

24. A folding machine having, in combination, a frame comprising a body portion, a forwardly extending portion and a portion overhanging the forwardly extending portion, folding and feeding means mounted upon the forwardly extending portion, a snipping knife mounted upon the overhanging portion, a driving shaft mounted in the body portion having a forwardly extending crank pin for operating the folding and feeding means, and means housed by the overhanging portion connecting the snipping knife to the driving shaft so as to be operated thereby.

25. A folding machine comprising mechanism for feeding and for folding down the edge of sheet material, and a knife for producing spaced snipping in the edge of the material as it is folded, at will, said knife being mounted upon the lever for actuating the lever about the adjustable ful-

being pivotally mounted upon a shiftable fulcrum and connected for manual control and adjustment during the folding operation so that the depth of the snip cuts may be varied at will without interfering with the operation of folding.

26. A folding machine comprising mechanism for feeding and for folding down the edge of sheet material, a snipping device connected for timed operation with respect to the feed of the material, said snipping device having a mounting movable to shift said device out of operative position, or into operative position, to variable degrees, to vary the depth of the snip cuts at will, and means for adjustably limiting the movement of the mounting in each direction of its movement.

27. A folding machine comprising mechanism for feeding and for folding down the edge of sheet material, and a snipping knife associated therewith carried on a lever connected for timed operation with reference to the feed of the material, said lever having a shiftable fulcrum with a manual control device therefor permitting said knife to be shifted variably at will into operative position, to change the depth of the snip cuts progressively with the machine in operation.

28. A folding machine comprising mechanism for feeding and for folding down the edge of sheet material, and a snipping knife associated therewith carried at the end of a lever connected for timed movement with reference to the feed of the material, said lever having a shiftable fulcrum permitting the operative range of said knife to be varied with an adjustable stop member to determine the maximum depth of snip cuts, and having also a treadle control device for shifting said fulcrum and thus varying the depth of said snip cuts, whereby the snipping may be initiated with relatively shallow cuts, progressing to a gradually increasing depth at will.

29. A folding machine comprising mechanism for feeding and for folding down the edge of sheet material, and a snipping knife for producing variable spaced snipping in the edge of the material as it is folded, at will, said knife being normally positioned so as to produce snips of maximum depth, and manual-controlled means for actuating the knife during the folding operation so that the depth of the snip cuts may be varied at will without interfering with the operation of folding.

30. A machine of the class described having, in combination, means for feeding and folding material, a swinging arm, a lever pivoted to the arm, whereby the point of pivotal connection of the lever to the arm constitutes an adjustable fulcrum for the lever, a knife mounted upon the lever for snipping the material, means for pivotally actuating the lever about the adjustable ful-

erum, and means for swinging the arm to adjust the position of the adjustable fulcrum.

31. A machine of the class described having, in combination, a frame, operative mechanism at one end of the frame, and a table encircling said mechanism pivoted to the frame at a point relatively removed from said end, whereby said table may be swung up over said end, out of the way of the operative mechanism.

32. A machine of the class described having, in combination, a frame provided with a platform at the forward end, feeding and folding means mounted near the platform, a table fitted around the platform pivoted to the frame at a point relatively removed from said end, whereby said table may be swung up over said end, out of the way of the platform, and means for adjustably supporting the forward end of the table.

33. A folding machine having, in combination, a frame, feeding mechanism at one end of the frame, a table encircling said mechanism pivoted to the frame at a point relatively remote from said end, whereby said table may be swung up over said end and out of the way of the feeding mechanism, and folding means associated with the feeding mechanism.

34. A folding machine comprising a machine frame or housing, feeding mechanism mounted and connected for vibration at a forward portion thereof, a forward projection of said frame extending around said feeding mechanism, a table encircling and adapted to fit over said forward projection,

and horizontally pivoted to the frame at a point relatively remote from the front thereof, whereby said table may be swung up over the front of the machine and out of the way of said feeding mechanism, and folding means associated with said feeding mechanism.

35. A folding machine having, in combination, means for pressing a fold in a sheet of material, means for feeding the material to the fold-pressing means step by step between limits of feeding movement, and means for causing both limits of movement to advance, each towards and away from the other, to vary the length of the feed strokes.

36. A folding machine having, in combination, means for pressing a fold in material, and means for feeding the material to the pressing means comprising a transversely movable leaf spring and a feed point carried by the leaf spring.

37. A folding machine having, in combination, means for folding material, means for pressing the folded material, and means for feeding the material to the fold-pressing means comprising a substantially horizontally disposed arm having a feed point at its outer end constructed and arranged to engage the material with yielding pressure, means for operating the arm back and forth in the line of feed, and a positive connection between the arm and the operating means.

In testimony whereof, we have hereunto subscribed our names.

CHARLES G. BROSTROM.

ANDREW R. RIDDERSTROM.
